UNITED STATES PATENT OFFICE

GUSTAVE E. FRANQUIST, OF ROCHESTER, NEW YORK; MARGARET LOUISE FRANQUIST, EXECUTRIX OF SAID GUSTAVE E. FRANQUIST, DECEASED, ASSIGNOR TO THE CLEVELAND TRUST COMPANY, OF CLEVELAND, OHIO

PISTON

Application filed May 26, 1922. Serial No. 563,782.

This invention relates to engines, steam, internal combustion, etc. and is an improvement on my earlier piston on which U. S. Letters Patent No. 1,153,902 was granted and 5 relates to any type of piston having a head and a skirt, and in which said head and skirt are separated partially or otherwise on the peripheral surface by a circumferential slot or groove. My previous invention was based 10 on the belief that very largely the trouble experienced with pistons prior to that time, under operating conditions was due, not to the relatively large expansion of the skirt on account of its thermal expansion attributable 15 to the heat conducted to it from the head, but rather due to the radial forces created by the very great thermal expansion radially of the head.

In my earlier invention I have shown the 20 means now widely followed to permit the snug fitting of a piston skirt within the cylinder, thus eliminating piston slap at all speeds and temperatures of the engine, and at the same time insuring against seizure, 25 or piston or cylinder scoring, or both. On further analysis of the problem, I concluded that such a piston might be fitted successfully even more closely within the cylinder if the piston skirt were properly relieved.

30 Relief may be termed an exterior peripheral under-cutting of the portions of the piston skirt so that such portions will not come into contact with the cylinder wall. In view of the radial expansion of the head, each element 35 of the complete or incomplete cylinder, which is the piston skirt, would tend to move radially outward from the upper or head end of the skirt in decreasing measure to the bottom of the skirt or open end, except where the continuity of the elements from piston head to 40 skirt is broken physically which is actually the case with all elements lying between the element intercepted by the chord of the arc representing the extent of the circumferential 45 separating slot. However, due to the rigidity of the piston structure in general, the relief circumferentially should extend well beyond the elements in question, that is, well over onto the peripheral surface of the independ-

50 ently functioning portions of the piston skirt.

In other words, the elements bounding the circumferential extent of the relief, extends beyond the elements cut by the circumferential separating groove or slot with respect to their respective circumferential distances from the piston pin axis. This is true, 55 not only of the exact piston structure shown in my Patent No. 1,153,902, but in cases where the ribs are replaced by other means such as webs, or struts connecting or supporting the independently functioning parts of the skirt with respect to the other portions of the piston. In those cases where there is a rigid strut or web transversely across the wrist pin boss, it is increasingly necessary 60 to carry this relief well beyond the intercepted element since in those cases the actual lengthwise expansion of the webs or struts due to the heat conducted thereto from the head, will tend to carry these portions of the skirt at the extremities of such web or struts directly into the cylinder wall, resulting 65 either in increased frictional losses, or the necessity of fitting the piston skirt within the cylinder with greater clearances, an undesirable condition and one the design is expected to overcome.

The longitudinal extent of this relief may be the entire length of the piston skirt or not. It is very important, however, that the piston skirt should be well relieved in those portions immediately adjacent to the piston head.

70 My theory has been substantiated in every respect in that I find I can fit a piston with considerably less clearance with the relief as indicated than is possible with the relief not extending beyond the elements in question. In one particular case it was possible to reduce the clearance from .005" to .003", 75 whereas with an ordinary piston, that is one not constructed in accordance with my original patent, a clearance of .009" to .010" was necessitated.

80 In the accompanying drawings, Fig. 1 shows a front elevation of a piston constructed with the relief designed in accordance with this invention.

85 Fig. 2 is a side elevational view of the piston shown in Fig. 1.

Fig. 3 is a sectional view of a piston of the type shown in my prior patent externally relieved in accordance with my present invention.

5 Fig. 4 shows the application of my present invention to a construction in which struts or webs take the place of the radial ribs shown in my previously mentioned prior patent.

10 Fig. 5 shows the application of my present invention to a construction in which the relief takes the form of an actual change in the contour of the piston and in which the independently functioning portions of the skirt are supported from struts or webs that take the place of the radial ribs shown in my prior patent.

15 Fig. 6 is a view in perspective of a piston of somewhat different form illustrating an additional application of my invention.

20 Fig. 7 is a front elevational view of a piston having its relieved area extending to the bottom of the skirt in accordance with this invention.

25 Fig. 8 is a side elevational view of the piston shown in Fig. 7; and

Fig. 9 is a view in perspective of a piston of the form shown in Fig. 5 with the relief extending to the bottom of the piston skirt.

30 Referring to the drawings, 1 in all cases is the piston head. 2 is the piston skirt. 3 is the relief. 4 is a circumferential separating slot. For our purposes the piston head is to be considered the part above the circum-

35 ferential slots, the skirt the part below it. 5 represents a longitudinal slot or groove, 6 represents the rib, web or strut forming the support of the independently or partially independently functioning portions of the skirt. It will be noted that the relief 3 in all cases is carried well beyond the supporting or attaching medium 6. The portions of the piston skirt adjacent to the wrist pin bosses and physically integral with the pis-

40 ton head are subject to the mechanical expansion produced by the thermal expansion of the head 1, and this expansion acts radially in all directions, and all elements on skirt 2, will be moved mechanically outward except where the elements are cut, due to the rigidity of the supporting medium 6; these will be moved outwardly also for some little

45 distance past the point where the elements are actually cut by the circumferential slot

50 4. In practice the length of the chord subtending this circumferential slot will vary, but in all cases, relief 3 should extend well beyond it. Chords 7-7 show the arc subtended by the circumferential slot 4 in the cases represented by Fig. 4 and Fig. 5.

55 It is not my purpose to confine my invention to any particular form of relief. This may be a reduced diameter, or there may be an actual change in the contour of the piston at this point, or this relief may be a maxi-

60 mum adjacent and opposite the wrist pin bosses gradually decreasing to nothing at the proper point beyond the elements cut by aforesaid circumferential slots.

65 What I claim as new and desire to claim by Letters Patent is:

70 1. A piston for an internal combustion engine, comprising, a head and a skirt, piston pin bosses projecting from the interior of said skirt, said skirt having longitudinally disposed grooved ribs arranged between said wrist pin bosses and the cylinder engaging walls of the skirt having its cylinder wall engaging section separated from said head by circumferentially arranged slots, the external surface of said skirt being relieved continuously and from points opposite said wrist pin bosses to points beyond the walls of said longitudinal groove at either side of each said boss.

75 2. A piston for an internal combustion engine, comprising, a head and a skirt, piston pin bosses projecting from the interior of said skirt, said skirt having longitudinally disposed grooved ribs arranged between said wrist pin bosses and the cylinder engaging walls of the skirt having its cylinder wall engaging section separated from said head by circumferentially arranged slots, the walls 80 of said skirt being relieved continuously from points intermediate said cylinder engaging sections and the wall adjacent one of said grooves toward the vertical plane of the axis of the adjacent pin boss.

85 3. A piston for an internal combustion engine comprising a head portion having a ring flange depending therefrom, and a skirt portion having oppositely disposed cylinder bearing portions with boss carrying portions intermediate said cylinder bearing portions 90 and joined thereto by web portions, each of said boss carrying portions being integrally joined to the head portion, each of said cylinder bearing portions being separated from the head portion by a circumferential slot 95 formed adjacent said ring flange and terminating at the connection of said boss portion to said head portion, the skirt portion being substantially relieved in the zone of each of said boss portions over an area including the web portions adjacent each of said boss portions.

100 4. A piston for an internal combustion engine comprising a head portion having a ring flange depending therefrom, and a skirt portion having oppositely disposed cylinder bearing portions and boss carrying portions intermediate said cylinder bearing portions 105 and joined thereto by web portions, each of said boss carrying portions being integrally joined to the head portion, each of said cylinder bearing portions being separated from the head portion by a circumferential slot 110 formed adjacent said ring flange and terminating at the base of said boss portion, the 115

6 cylindrical surface of said skirt portion being substantially relieved in the zone of each of said boss portions over an area extending beyond the terminae of the said circumferential slots on the corresponding side of said skirt.

5. A piston for an internal combustion engine comprising a head having a ring flange depending from the periphery thereof, a skirt having oppositely disposed cylinder

10 engaging walls and oppositely disposed wrist pin carrying sections arranged between said cylinder engaging walls and integrally connected to said head, the skirt section being

15 separated from the head section by circumferential slots extending at either end beyond the adjacent boundaries of said cylinder engaging walls, webs connecting the cylinder engaging walls and the boss carrying

20 sections, the skirt section being relieved on opposite sides over areas including the web sections and adjacent wrist pin bosses and said circumferential slots extending into said relieved areas at either side of the piston.

25 6. A piston for internal combustion engines having in combination a head section and a guide section comprising diametrically opposite cylinder engaging portions separated from the head section by air gaps and

30 intermediate portions formed with wrist pin bosses and connected at their upper ends to the head sections, said intermediate portions also being formed to have no contact with the cylinder from their upper ends to points be-

35 low the bosses and being adapted when the head expands to apply stresses to said cylinder engaging portions in a manner tending to draw them toward each other.

7. A piston for internal combustion engines having a head and a sleeve, transverse

40 slots in diametrically opposite sides of the piston separating the opposite side portions of the head from the sleeve, whereby the head is connected to the sleeve between the ends

45 of the slots, the sleeve being slightly elliptical in general form in cross section, the ends of the elliptical form being concentric with the axis of the piston, and wrist pin bosses projecting from the portions of the sleeve joined to the head between the ends of the slots, the axis of said pin bosses extending along the short diameter of the elliptical form, substantially as and for the purpose specified.

8. A one piece piston comprising a head and a skirt, the skirt having boss carrying

50 portions exteriorly relieved and arranged opposite each other and secured to the head by substantially rigid connectors to cause radial-

55 ly outward and inward movement of the portions under operation conditions of the piston, the skirt also having opposite bearing wall portions arranged between the said boss carrying portions and each separated from

65 the head by a slot of greater circumferential

length than the corresponding length of the said portions.

9. A piston comprising a head and a substantially continuous skirt connected thereto, the skirt having boss carrying wall portions, exteriorly relieved, and bearing wall portions, each bearing wall portion being separated from the head by a slot extending not less than about 10° beyond either side of the said portion.

10. A piston comprising a head and a substantially continuous skirt connected thereto, the skirt having boss carrying wall portions, exteriorly relieved, and bearing wall portions approximately 60° in circumferential length, each bearing wall portion being separated from the head by a continuous circumferential slot extending not less than about 10° beyond either side of the said portion.

11. An integrally formed piston for internal combustion engines comprising in combination a head portion having a circumferentially depending ring flange, a guide portion having diametrically opposite cylinder engaging parts for taking the angular thrust of a connecting rod, each being circumferentially separated from said ring flange, oppositely disposed wrist pin bosses depending from said head portion and extending between adjacent longitudinal ends of said cylinder engaging parts, and integral webs extending between said adjacent longitudinal ends and being integral with said bosses, each of said cylinder engaging parts being circumferentially extended beyond the connections of said webs therewith, and each being circumferentially relieved on its exterior surface from its extreme longitudinal edges to points substantially beyond the connections of said webs therewith.

12. An integrally formed piston for internal combustion engines comprising in combination a head portion having a circumferentially depending ring flange, a guide portion having diametrically opposite cylinder engaging parts for taking the angular thrust of a connecting rod, each being separated from said ring flange by a circumferential slot, oppositely disposed wrist pin bosses depending from said ring flange and extending between adjacent longitudinal ends of said cylinder engaging parts, and a pair of longitudinal parallel webs, integral with said

wrist pin bosses, each extending between adjacent longitudinal ends of said cylinder engaging parts perpendicular to the axis of said wrist pin bosses, and each being integrally connected with said ends a substantial distance from the marginal edges thereof, each of said cylinder engaging parts being exteriorly relieved from said longitudinal marginal edges to points well beyond the planes of connection of said webs therewith.

13. In a piston open at one end and hav-

- ing a packing ring supporting portion, a cylinder engaging portion, comprising oppositely disposed circumferential sections separated from said ring supporting portion by 5 circumferential slots, a pair of wrist pin bearings depended from said ring supporting portion separated from said cylinder engaging sections, and tying means extending from each of said wrist pin bearings, each 10 tying means being cooperably connected at their opposite ends to said cylinder engaging sections inwardly from the longitudinal marginal edges, the longitudinal ends of each of said sections being exteriorly relieved 15 circumferentially from the edges thereof to points beyond the connections of said tying means therewith and longitudinally from the lower edges thereof to the circumferentially separating slot.
- 20 14. In an internal combustion engine, a head having a ring flange, a longitudinal skirt having oppositely disposed boss carrying portions integral with said ring flange and opposite bearing wall portions between 25 said boss carrying portions, each bearing wall portion being separated from said ring flange by a circumferential slot of greater length than the corresponding length of the said portion, wrist pin bosses extending inwardly from said boss carrying portions, reinforcing ribs extending longitudinally within said skirt adjacent each side of each of said wrist pin bosses, and longitudinal slots in the external surface of said skirt extending into each of said ribs, the external surface of said 30 skirt being relieved the full length thereof and continuously from points opposite said wrist pin bosses to points beyond the walls of said longitudinal slot at each side of each of said bosses.
- 35 15. In an internal combustion engine, a head having a ring flange, a longitudinal skirt having oppositely disposed boss carrying portions integral with said ring flange and opposite bearing wall portions arranged 40 between said boss carrying portions, each bearing wall portion being separated from said ring flange by a circumferential slot of greater length than the corresponding length of the said portion, wrist pin bosses extending inwardly from said boss carrying portions, reinforcing ribs extending longitudinally within said skirt adjacent each side of each of said wrist pin bosses, and longitudinal slots in the external surface of said skirt extending into each of said ribs, the slots at one side of said bosses extending from the open end of said skirt to the ends of the said circumferential slot at that side, and the 45 slots at the other side of said bosses extending from the open end of said skirt to the ends of the other of said circumferential slots, the external surface of said skirt being relieved continuously and from points opposite said 50 wrist pin bosses to points beyond the walls 55
- of said longitudinal slot at each side of each of said bosses.
16. In an internal combustion engine, a head having a ring flange, a longitudinal skirt having oppositely disposed boss carrying portions integral with said ring flange and opposite bearing wall portions between said boss carrying portions, each bearing wall portion being separated from said ring flange by a circumferential slot of greater length than the corresponding length of the said portion, wrist pin bosses extending inwardly from said boss carrying portions, reinforcing ribs extending longitudinally within said skirt adjacent each side of each of said wrist pin bosses, and longitudinal slots in the external surface of said skirt extending into each of said ribs, the external surface of said skirt being relieved the full length thereof and continuously from points opposite said wrist pin bosses to points beyond the walls of said longitudinal slot at each side of each of said bosses.
- 60 In testimony whereof, I affix my signature.
- GUSTAVE E. FRANQUIST.
